(57) **CLAIM**

The ornamental design for a bed, as shown and described.

DESCRIPTION

FIG. 1 is a left front perspective view of a bed showing my new design;

FIG. 2 is a side perspective view, the opposite side being a mirror image thereof;

FIG. 3 is a front elevational view of a headboard taken along line 3—3 in FIG. 2;

FIG. 4 is a front elevational view of a footboard; and,

FIG. 5 is a rear perspective view of the bed.

The broken lines showing the bed rails is for illustrative purposes only and forms no part of the claimed invention.
